DISINTEGRATING AND CONVEYING CHAIN

Joseph F. Joy, Pittsburgh, Pa., assignor to Joy Manufacturing Company, Pittsburgh, Pa., a corporation of Pennsylvania

Application March 29, 1949, Serial No. 84,128

5 Claims. (Cl. 262—33)

1

This invention relates to mining chains and more particularly to a disintegrating and conveying chain adapted for use with the vein-attacking and disintegrating head of a continuous mining apparatus.

In a continuous mining apparatus of the type disclosed in the copending applications to John D. Russell, Ser. No. 47,421 and John R. Sibley, Ser. No. 47,422, now abandoned, which have been replaced by continuation-in-part applications Ser. Nos. 102,995 and 102,996, respectively, both filed on July 5, 1949, and owned by applicant's assignee, a mine vein-attacking and disintegrating head is provided for attacking in succession a series of relatively wide, vertical segments of coal or other mineral for dislodging the latter in relatively large fragments from a solid coal seam or mine vein. The attacking and disintegrating head includes a bar structure providing guideways on which a series of parallel disintegrating chains are guided for circulation in vertical orbital paths and these chains carry disintegrating instruments which dig into and rip or tear out the coal or other mineral as the attacking and disintegrating head is fed in a suitable manner with respect to the face or seam or vein, as is fully disclosed in the applications above referred to. The present invention contemplates improvements over known types of disintegrating chains whereby the attacking and disintegrating head may be fed to effect disintegration of the solid coal or other mineral in an improved and extremely effective manner. The disintegrating and conveying chain of the present invention is of the so-called continuous mat type formed to receive and convey disintegrated material, and is extremely compact and rugged in design, and may be operated rapidly and relatively smoothly to dislodge the coal or other mineral from the solid and to convey the disintegrated coal or other mineral rapidly away from the face as it is dislodged, thereby greatly expediting the production of coal or other mineral.

An object of the present invention is to provide an improved mining chain constructed in a novel manner and carrying disintegrating instruments whereby coal or other mineral may be dislodged from the solid in an extremely effective manner. Another object is to provide an improved disintegrating and conveying chain of the so-called continuous mat type whereby relatively great strength, due to ruggedness in design, and extreme compactness are attained. Still another object is to provide an improved disintegrating chain for the vein-attacking and disintegrating head of a continuous mining apparatus, whereby, due to the relatively smooth operation of the chain, vibrations set up within the apparatus during the dislodging operation are reduced to a minimum. A further object is to provide an improved continuous mat type disintegrating and conveying chain having a series of closely spaced, cooperating chain elements

2

which provide a top surface for receiving and conveying disintegrated material. Still another object is to provide an improved mat type disintegrating and conveying chain having a series of closely spaced, hinged chain elements which include at spaced points along the length of the chain a series of transverse supporting means for disintegrating instruments. A still further object is to provide an improved disintegrating and conveying chain carrying at spaced points along its length, by said supporting means, detachable cross bars which carry digging or disintegrating teeth, and which may be readily detached from the chain in the event the teeth need reforming or sharpening. Yet another object is to provide an improved disintegrating and conveying chain for a continuous mining apparatus, which carries at points spaced along its length, transverse supporting means providing transverse guideways for receiving elongated cross bars each of which carries a series of digging and disintegrating teeth. Another object is to provide an improved releasable means for securing the cross bars in operative position on the transverse supporting means and which may be readily released to permit removal of the cross bars. Yet another object is to provide, in an endless disintegrating and conveying chain of the above character, supporting means which comprise transverse rows of closely spaced chain blocks having aligned guideways for receiving the toothed cross bars. A further object is to provide a detachable cross bar for a disintegrating chain which carries a series of disintegrating teeth which are suitably hard faced or otherwise provided with wear resisting disintegrating points whereby relatively long life and improved efficiency are obtained. A still further object is to provide an improved endless disintegrating and conveying chain of the continuous mat type having novel features of construction. These and other objects and advantages of the invention will, however, hereinafter more fully appear in the course of the ensuing description.

45 In the accompanying drawings there are shown for purposes of illustration two forms which the invention may assume in practice.

In these drawings:

Fig. 1 is a plan view of a continuous mining apparatus, with the rearward portion broken away, within which a preferred illustrative embodiment of the invention is incorporated.

Fig. 2 is a side elevational view of the mining apparatus shown in Fig. 1.

Fig. 3 is an enlarged horizontal sectional view taken substantially on the planes of line 3—3 of Fig. 2.

Fig. 4 is an enlarged view in central longitudinal vertical section taken substantially on line 4—4 of Fig. 1, showing the vein-attacking and disintegrating head.

Fig. 5 is a cross sectional view taken on line 5—5 of Fig. 4, illustrating the details of a pre-

furred form of the improved disintegrating and conveying chain.

Fig. 6 is a fragmentary plan view of a section of the improved disintegrating and conveying chain shown in Fig. 5.

Figs. 7 and 8 are cross sectional views taken respectively on line 7—7 and 8—8 of Fig. 6, illustrating structural details.

Fig. 9 is an enlarged detail section taken on line 9—9 of Fig. 6, showing the toothed cross bars.

Fig. 10 is an enlarged side elevational view of the chain section shown in Fig. 6.

Fig. 11 is a fragmentary sectional view, similar to Fig. 4, showing the vein-attacking and disintegrating head equipped with a disintegrating and conveying chain of modified construction.

Fig. 12 is a fragmentary plan view of the disintegrating and conveying chain shown in Fig. 11, on a larger scale.

Figs. 13 and 14 are enlarged detail sectional views taken on lines 13—13 and 14—14 respectively of Fig. 12.

Fig. 15 is a cross sectional view taken on line 15—15 of Fig. 12.

In this illustrative construction, as shown in drawings, the improved disintegrating and conveying chain is shown incorporated in a continuous mining apparatus of the type fully disclosed in the above mentioned Russell and Sibley applications. The improved disintegrating and conveying chain is also of a type which may be associated with continuous mining apparatus such as that disclosed in an earlier filed application of Harold F. Silver, Ser. No. 11,688, filed Feb. 27, 1948, also owned by applicant's assignee, and it will further be understood that the invention may be embodied in various other types of digging and disintegrating equipment.

The continuous mining apparatus shown herein is generally designated 1 and includes a mobile base 2, desirably a crawler base, having a frame 3, and swivelly mounted on the base frame at 4 to swing in horizontal planes with respect to the base is a frame 5. The swivelled frame 5 has a forwardly projecting frame portion 6 projecting in advance of the base and providing horizontal guideways on which a slidable frame 7 is guided for rectilinear horizontal movement along radial lines with respect to the swivel axis 4. Pivotally mounted at 8 on the sliding frame to swing in vertical planes with respect thereto is a frame or bar structure 9 of a vein-attacking and disintegrating head, and the improved disintegrating and conveying chain generally designated 10 is guided for circulation in a vertical orbital path about guideways on the frame structure 9. The attacking and disintegrating head may be operated to dig into and tear loose large fragments of the solid coal or other mineral from the coal seam or mine vein and the disintegrated material is moved rearwardly by the top run of the disintegrating and conveying chain and discharged onto a front conveyor 11 which conveys the disintegrated material rearwardly to discharge into a hopper 12 arranged coaxially with the swivel 4 and carried by the base frame. A rear discharge conveyor 13 removes the disintegrated material from the hopper and conveys the disintegrated material rearwardly of the apparatus to a suitable point of delivery. A gathering device or shovel 14 is carried by the sliding frame 7 beneath the attacking and disintegrating head, for cleaning up the floor in advance of the base,

and any loose material on the floor may be directed rearwardly by the gathering device onto the front conveyor 11.

As is fully disclosed in the above mentioned Russell and Sibley applications hydraulic cylinder and piston devices 16, 16 mounted transversely on the base are operatively connected to the frame 5 for swinging the attacking and disintegrating head horizontally about the swivel axis 4 relative to the base. Hydraulic cylinder and piston devices 17, 17 extending longitudinally in parallelism on the swivelled frame 5 are operatively connected to the sliding frame 7 for moving the attacking and disintegrating head back and forth along the frame guideways. Hydraulic cylinder and piston devices 18 are connected between the sliding frame and the frame structure 9 for swinging the attacking and disintegrating head in vertical planes about the pivot 8. A hydraulic cylinder and piston device 19 is provided for tilting the gathering device 14. Since these cylinder and piston devices and the control valve means therefor are fully disclosed in the above mentioned Russell and Sibley applications further description thereof is herein unnecessary.

As is also disclosed in the Russell and Sibley applications above referred to, motors 21, 21 on the swivelled frame 5 at the opposite sides of the hopper 12, are connected by self-adjusting, telescopic drive shaft connections 22 to longitudinal shafts 23 suitably journalled in gear housings 24 attached to the opposite sides of the forward portion of the sliding frame 7. Gears 25 fixed to these shafts mesh with gears 26 secured to parallel shafts likewise suitably journalled in the gear housings. Secured to these parallel shafts are worms (not shown) meshing with worm wheels 27 which drive gears 28 meshing with gears 29 keyed to the opposite ends of a transverse shaft 30, arranged with its axis in coincidence with the pivotal axis 8 of the swingable frame structure 9. A multiple-toothed sprocket 31 is splined to the shaft 30 and engages and drives the disintegrating and conveying chain 10, to effect circulation of the latter about the guideways on the frame structure with its upper run moving rearwardly. The frame structure 9 includes top and bottom plates 32 and 33 and carried at the outer end of the frame structure is a guide roller 34 and the disintegrating and conveying chain is guided along these plates and about the guiding roller. Since the driving means for the disintegrating chain and bar structure are fully disclosed in the Russell and Sibley applications further description thereof is herein unnecessary.

Now referring to the improved disintegrating and conveying chain shown in Figs. 1 to 10 inclusive it will be noted that the chain comprises a series of closely spaced, narrow, elongated cross supports or chain blocks 35 herein arranged in transverse rows across the width of the chain at points spaced lengthwise of the latter, and the end blocks of each row, at the sides of the chain, have lateral gibs 36 which are slidably received in the guideways of the frame structure 9, in the manner shown in Fig. 5. The supports or chain blocks 35 of each transverse row have front and rear perforated lug portions 37 for receiving parallel pivot rods 38. These rods are formed with heads 39 at one end and are hammered or peened over at 40 at their opposite ends as shown in Figs. 7 and 8. Projecting between the spaced lug portions of the chain blocks and pivotally en-

gaging the pivot rods are series of closely spaced parallel connecting links or straps which connect the chain blocks together to form an endless chain. The pivot rods maintain the straps and blocks against lateral displacement. The spaces 43 between the straps 42 receive the teeth of the drive sprocket (Fig. 4), with the teeth drivingly engaging the end surfaces of the chain blocks in an obvious manner. The numerous connecting links in conjunction with the series of chain blocks and the close spacing of the links and blocks result in an endless chain of the extremely compact and rugged mat type which provides a substantially continuous, moving top surface for receiving and conveying disintegrated material as it is dislodged from the solid. The chain blocks of each transverse row have aligned transverse guideways which receive cross bars or slides 45 which are formed with a series or transverse row of laterally spaced digging or disintegrating teeth 46. Thus the blocks of each transverse row cooperate to provide transverse supporting means for a toothed cross bar. Evidently, instead of the provision of a series of transverse rows of chain blocks, a series of single cross links may be employed and each cross link may have series of closely spaced front and rear perforated lugs for receiving the pivot pins, and each cross link may have an elongated guideway for receiving a toothed cross bar. The intermediate teeth of each cross bar are desirably arranged normal to the path of chain travel while the side teeth are inclined laterally, and the teeth on certain ones of the cross bars are staggered with respect to the teeth of others to provide for proper "lacing" of the teeth in a well-known manner. In the construction disclosed every other one of the cross bars is of slightly greater length than the others, as shown in Figs. 6, 7 and 8, and the outer teeth of the longer cross bars are inclined outwardly at a substantial angle, in the manner shown. Desirably the disintegrating points 47 of the teeth are hard faced at 48 or otherwise provided with wear resisting surfaces. When the cross bars are properly slid into place within the guideways of the chain blocks a pair of set screws 49 on each cross bar are adjustable into apertures 50 in the adjacent chain blocks for rigidly securing the cross bars in position on the chain. In the event the teeth of the cross bars need reforming or sharpening as the result of wear or breakage the set screws may be released to permit ready endwise withdrawal of the cross bars from the chain block guideways. It will be noted that the tips of the teeth lie relatively close to the chain links, so that lever action is minimized during disintegration of the coal or other mineral, thereby reducing the binding tendency and increasing the ruggedness of the chain.

In the modified construction shown in Figs. 11 to 15 inclusive the chain blocks and straps and the chain block guideways are similar to those above described. In this instance, the cross bars or slides 53 have on their outer surfaces laterally spaced lugs 54 formed with longitudinal sockets 55 opening through the front and rear ends of the lugs (Fig. 13). A double ended, reversible disintegrating bit 56 of the type disclosed in my copending application Ser. No. 57,047, filed October 23, 1948, has a body formed by relatively inclined portions 57 and 58 disposed at an obtuse angle and terminating in disintegrating points 59 at the opposite extremities of the bit. The front faces of the disintegrating points are, in this instance, formed with hard metal inserts 60 or other

hard material for resisting wear. The cutter bit is reversible and either portion of the bit body is receivable in the lug sockets, and set screws 61, threaded in top openings in the lugs, are adjustable into engagement with the inactive bit portions received in the lug sockets for securing the bits in position on the cross bars with the active disintegrating points extending forwardly and outwardly from the lugs in the manner shown. 5 The lugs are so arranged on the cross bars that a desired staggered relation of the bits on the chain is provided. Set screws 63 threaded in the cross bars are adjustable into apertures 64 in certain of the chain blocks for securing the cross bars in position on the chain blocks, in a manner similar to the embodiment above described. The set screws 63 may be released to permit endwise withdrawal of the cross bars from the chain blocks of the chain. When one disintegrating point of a bit becomes dull the set screw 61 may be released and the bit withdrawn from the lug socket, and the bit may then be reversed end for end and reinserted in the lug socket and secured in position by the set screw in the manner fully 10 disclosed in my copending application Ser. No. 57,047 above referred to.

In both embodiments the disintegrating and conveying chain during use is rapidly circulated about its guideways on the swingable frame or bar structure 9 and the chain links of the top run of the chain move along the flat outer surface of the top plate 32 with the tips of the disintegrating teeth, as the chain links move rectilinearly along the top plate, lying substantially in a common transverse plane to provide what is known as a "table top" arrangement of the teeth. The teeth move in a curved path as they pass around the roller 34 at the outer end of the bar structure and then move rearwardly along a rectilinear path so that as the chain is fed into the coal or other mineral the latter is rapidly dislodged in relatively large fragments, efficiently and relatively smoothly.

As a result of this invention an improved mining chain is provided which is not only efficient in operation but is extremely rugged and compact and which has disintegrating teeth which may be quickly reformed or sharpened when desired. By the provision of the improved chain link structure an endless chain of the continuous mat type is provided having a moving upper surface for receiving and conveying disintegrated material. The novel structure of the chain blocks, straps and cross bars and the novel arrangement of the disintegrating teeth on the latter, result in a simplified and extremely rugged chain design. By mounting transverse rows of disintegrating teeth on the cross bars and by releasably mounting the cross bars in guideways on the chain blocks rapid assembly and dismantling of the teeth are possible. By forming the disintegrating teeth with wear resisting disintegrating points the life and cutting efficiency of the teeth are greatly improved. By the provision of the mat type construction it is possible to reduce the vertical dimension of the bar structure and reduce the size of the drive sprocket and guiding roller so that the curvature of the path of the chain at the outer extremity of the bar is maintained at a minimum resulting in an improved dislodging action on the coal or other mineral to be dislodged. Other advantages of the invention will be clearly apparent to those skilled in the art.

While there are in this application specifically

described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. A disintegrating and conveying chain of the relatively flat and wide endless mat type especially designed for mining purposes, comprising a series of relatively narrow, elongated transverse chain link members spaced apart in parallelism longitudinally of the chain and extending crosswise substantially the full width of the chain and a series of closely spaced relatively narrow chain links pivotally connected to said transverse link members, said link members and said links cooperating to provide a chain of substantially greater width than its height having an upper conveying surface of substantial area, each of said parallel transverse link members having series of closely spaced front and rear lugs perforated by aligned parallel, front and rear openings for receiving elongated hinge pins, said links fitting closely between said lugs and pivotally engaging said hinge pins, said parallel transverse link members each having a transverse guideway extending lengthwise thereof completely there-across and including parallel front and rear guide flanges at the outer surface thereof, elongated cross bars having lateral guides freely insertable from a side of the chain endwise within said guideways in engagement with said flanges into coextensive relation with said transverse link members and each cross bar having a series of laterally spaced disintegrating teeth distributed along its length at the outer surface of the chain, and cooperating releasable means carried by said cross bars and said link members for securing said cross bars in position on said link members to prevent endwise displacement thereof from said guideways and releasable at will to permit free removal of said cross bars in any chain position without dismantling said link members, links and hinge pins.

2. A disintegrating and conveying chain of the character set forth in claim 1 wherein said transverse link members have lateral gibs at the ends thereof beyond the outermost lugs adapted for engagement with the guideways of a guide bar structure whereby said chain is guided for orbital circulation solely at its sides and its inner surface, and said cross link members providing the inner guide-engaging surface.

3. A disintegrating and conveying chain of the character set forth in claim 1 wherein certain of said cross bars have their disintegrating teeth staggered with respect to the teeth of the other cross bars, and certain of said cross bars provided with laterally inclined teeth at the ends thereof beyond the ends of said transverse guideways whereby the disintegrating chain may disintegrate solid material to remove a wide segment thereof of greater width than the chain guide of a bar structure with which the chain is adapted for association.

4. A disintegrating and conveying chain of the endless, relatively flat, endless mat type guided for circulation in a non-circular orbit, comprising a series of transverse chain link members spaced apart longitudinally of the chain and a series of relatively narrow closely spaced chain links pivotally connected to said

transverse link members whereby said link members and said links cooperate to provide a relatively large conveying surface of a width equal to several times the height of the chain, said link members being relatively narrow and elongated and extending substantially the full width of the chain, and each link member having a transverse guideway, a cross bar freely insertable endwise from a side of the chain into each guideway into coextensive relation with its cooperating link member and having a series of laterally spaced disintegrating teeth distributed along the length thereof, and releasable means on said cross bars and cooperating with said link members for securing said cross bars in position on said link members thereby to prevent endwise displacement of said cross bars from said guideways and releasable at will for permitting free removal of said cross bars in any position of the chain without dismantling said link members and links.

5. A disintegrating and conveying chain of the relatively flat and wide endless mat type especially designed for mining purposes, comprising a series of relatively narrow, elongated transverse chain link members spaced apart longitudinally of the chain and extending crosswise substantially the full width of the chain and a series of closely spaced relatively narrow chain links pivotally connected to said transverse link members, said link members and said links cooperating to provide an upper conveying surface of substantial area, each of said transverse link members having series of closely spaced front and rear lugs perforated by aligned parallel, front and rear openings for receiving elongated hinge pins, said links fitting closely between said lugs and pivotally engaging said hinge pins, said transverse link members each having a transverse guideway including parallel front and rear guide flanges at the outer surface thereof, elongated cross bars having lateral guides insertable endwise within said guideways in engagement with said flanges and each cross bar having a series of laterally spaced disintegrating teeth distributed along its length, and cooperating means carried by said cross bars and said link members for securing said cross bars in position on said link members to prevent endwise displacement thereof from said guideways, said securing means including a set screw threaded in an opening in each cross bar intermediate certain of the disintegrating teeth and an aperture in the associated link member at the bottom of the guideway therein for receiving the inner end of said set screw.
